JOHN EDWARD MULHOLLAND, OF PROVIDENCE, RHODE ISLAND.

ROVING STOP MOTION FOR SPINNING FRAMES.

1,401,984.

Specification of Letters Patent.

Patented Jan. 3, 1922.

Application filed April 29, 1921. Serial No. 465,511.

To all whom it may concern:

Be it known that I, GREGORE K. KAPATAS, a citizen of Greece, residing at Providence, in the county of Providence and State of Rhode Island, have invented a new and useful Improvement in Roving Stop Motions for Spinning Frames, of which the following is a specification.

In the usual construction of spinning frames the roving, when breaking in front of the top rolls, will usually wind up on the rolls or feed out of the rolls and snarl up on the bobbins or adjacent roving, also the roving may run to waste a considerable length of time before being noticed by the operator, thereby causing a material amount of waste.

The object of my invention is to improve the construction of a spinning frame, whereby when the roving breaks in or in front of the drawing rolls, it will be automatically held or broken, back of the top rolls, thereby preventing the feeding of the broken roving through the rolls.

My invention consists in the peculiar and novel construction of a roving stop-motion for spinning frames, whereby when the roving breaks between or in front of the drawing rolls it will be automatically stopped from feeding through the rolls, said stop-motion having details of construction, as will be more fully set forth hereinafter and claimed.

Figure 1 is a front view of part of a spinning frame provided with my improved roving stop-motion and showing the top rolls removed.

Figure 2 is a side view of Figure 1 partly in section and showing the roving stop-motion engaging with the roving in its normal position in full lines, and in the position it would assume in stopping the roving from feeding through the drawing rolls, in dotted lines, after the roving has broken or separated, and

Figure 3 is a top view of my improved roving stop-motion, enlarged relative to Figure 2.

In the drawings 4 indicates a portion of a spinning frame having the usual drawing rolls 5, eye 6, ring-rail 7, ring 8 bobbin 9 and spindle 10 operated in the usual way and 11 my improved roving stop-motion. The standard for the drawing rolls 5 carries the 55 usual round standard bar 12. The roving

R comes from the usual quills, not shown, over the round bar 12, through the drawing rolls 5, the eye 6 and ring 8, as shown in Figure 2 and is then wound on the bobbin 9, in the usual way.

My improved roving stop-motion 11 consists of a vertical pivot support 13 secured to the frame 4 under the drawing rolls 5. A light normally horizontal rod 14 is pivotally secured intermediate its length, to the upper end of the support 13 and a light normally horizontal rod 15 having a forked forward end 16 is pivotally secured at its inner end to the forward end of the rod 14, a finger 17 on the rod 15 extending under the end of the rod 14 holds the rod 15 from dropping downward and allows for raising of the rod 15, for doffing. A weight 18 is adjustably attached to the inner portion of the rod 14 for adjusting the tension of the forked forward end 16 on the roving. A vertical tubular rod 19 is pivotally secured at its lower end to the rear end of the rod 14 and carries a rod 20 which is adjustably secured in the tubular rod 19 by a set screw 21, and on the upper end of the rod 20 is fixed a curved clamping member 22 shaped to fit over the round bar 12, when in operation.

When in use, the roving R passes under and between the curved clamping member 22, and the standard bar 12, through the drawing rolls 5 and then down over the forked end 16 of the rod 15, the tension of the roving holding the rods 14 and 15 down and the clamping member 22 up away from the bar 12. When the roving breaks in the drawing rolls or in front of the drawing rolls, the tension of the roving is removed and the rods 19 and 20 dropping by gravity assisted by the weight 18, brings the curved clamping member down into engagement with the round bar 12, thereby clamping the roving between the curved clamping member and the round bar, and breaking the roving, before it can enter the drawing rolls, and preventing waste of the roving, and possible damage to adjacent roving and bobbins.

My improved roving stop-motion is extremely simple and inexpensive, it is adjustable and easily secured in place, one for each spindle.

It is evident that my improved roving stop-motion could be varied in construction, for different makes of spinning frames or

the like, within the scope of the appended claims.

Having thus described my invention I claim as new:—

- 5 1. In a spinning frame, a round bar forming an original part of the drawing rolls standard, a roving stop-motion comprising a pivot support secured to the frame of the machine, a light horizontal rod pivotally secured to the support and having a forked forward end engaging the roving in front of the drawing rolls, a vertical rod pivotally secured to the rear end of the horizontal rod and having a curved clamping member 10 shaped to fit over the round bar back of the drawing rolls, and over the roving and adapted to clamp the roving between the curved clamping member and the bar on the drawing rolls standard, for the purpose as 15 described.
- 10 2. A roving stop-motion for spinning frames, comprising a round bar forming an original part of the drawing rolls standard, a pivot support adapted to be secured to the

frame of the machine, a light normally horizontal rod pivotally secured intermediate its length to the pivot support, a light normally horizontal rod having a forked forward end pivotally secured at its inner end to the forward end of the first mentioned rod and having a finger extending under the end of the first mentioned rod, a weight adjustably attached to the inner portion of the first mentioned rod, a vertical tubular rod pivotally secured at its lower end to the rear end of the first mentioned rod and carrying a vertical rod adjustably secured by a set screw, and a curved clamping member on the upper end of the last mentioned vertical adjustable rod, said curved clamping member being curved to fit the round bar and to clamp the roving between the clamping member and the round bar on the drawing rolls standard, on the breaking of the roving, as described.

In testimony whereof, I have signed my name to this specification.

GREGORE K. KAPATAS.
